UNITED STATES PATENT OFFICE.

ARTHUR HENRY TOWNLEY, OF MANCHESTER, ENGLAND.

DEVICE FOR CLEANING SHAFTING.

1,230,629.

Specification of Letters Patent. Patented June 19, 1917.

Application filed November 7, 1916. Serial No. 130,034.

To all whom it may concern:

Be it known that I, ARTHUR HENRY TOWNLEY, a subject of His Majesty the King of England, and resident of Manchester, in the county of Lancaster, Kingdom of England, have invented a certain new and useful Device for Cleaning Shafting, of which the following is a specification.

This invention relates to a device for cleaning shafting and comprises a discoidal piece of slitted leatherboard, cardboard, or fiber, having a hole in its center for the accommodation of the shaft around which it is to be placed.

15 The invention is hereinafter described with reference to the accompanying drawings in which:—

Figure 1 represents the face of the disk complete;

20 Fig. 2 represents a section through the center of complete disk;

Fig. 3 represents the back of the complete disk;

Fig. 4 represents the complete disk in

25 position on a piece of shafting;

Fig. 5 represents the clip; and

Fig. 6 represents the plain disk showing the hole in its center, and the four square holes, two on each side of the cut.

30 As shown I provide a round or angular shaped piece of leatherboard, cardboard or other suitable material *a* with a round hole *b* in the center, such center hole to be suitably larger than the machinery shafting, around which it is to be placed and the leatherboard or other suitable material, hereinafter called the disk, being preferably coated with wax or other greaseproof or semi-greaseproof preparation. The disk *a* is 35 cut at *c* from the center hole *b* to the outside edge to allow of its being opened to admit the shafting. After the disk *a* has been placed around the shafting, the opening, or cut *c* is fastened or sealed, by a suitable clip 40 *e* such as that shown in Fig. 5 made in the shape of a cross with an extended center piece. The two short arms of the said clip *e* are bent up, and also one end of the extended center piece. One of these clips *e* is 45 then fixed in each of the two square holes *d*'

on one side of the cut *c* the bent short arms being pressed through and flattened outward on the surface of the disk. The holes *d'* and *d* are made of sufficient area to counterbalance any undue weight of the clips. 55 One end of the center piece remains at the back of the disk, the other end is taken past the cut to the other side, bent through the corresponding square holes *d* and pressed upward, thus sealing up the cut *c*. 60

The action of the machinery shafting in revolving will keep the disk upright and will cause it to traverse from pulley boss, to pulley boss or pedestal boss, reverse automatically, distributing the oil, or grease in 65 equal proportions and serving to keep the shafting bright and free from rust and dirt.

What I claim is:—

1. A device for cleaning shafting comprising a discoidal piece of slitted material 70 having a hole formed in its center and a plurality of cross shaped clips for uniting the divided ends of the material substantially as described.

2. A device for cleaning shafting comprising a discoidal piece of slitted leather board having a central opening and coated with a grease-proof preparation, the leather board having slots each side the slit, and means extending across the slit to hold the ends together. 75

3. A device for cleaning shafting comprising a discoidal piece of material formed with a central opening and radially slit, and means extending at right angles to the slit 85 including projections which pass through openings formed in the material each side of the slit to secure the divided ends of the material together.

4. A device for cleaning shafting comprising a discoidal piece of slitted material having a central opening and a plurality of slots adjacent the divided ends, and clips extending across the divided ends and engaging the plurality of slots, said clips having 95 bent portions to secure the same in position to hold the divided ends together.

In testimony whereof I have hereunto subscribed my name.

ARTHUR HENRY TOWNLEY.
